UNITED STATES PATENT OFFICE

157,316

BOTTLE CARRIER

Grant M. Acton, Arkansas City, Kans., assignor to
Acton Manufacturing Company, Inc., Arkansas
City, Kans., a corporation of Kansas

Application March 28, 1949, Serial No. 1,668

Term of patent 14 years

(Cl. D58—4)

To all whom it may concern:

Be it known that I, Clare E. Applegate, a citizen
of the United States, residing at Arkansas City, in
the county of Cowley and State of Kansas, have
invented a new, original, and ornamental Design
for a Bottle Carrier, of which the following is a
specification, reference being had to the accom-
panying drawings, forming part thereof.

Fig. 1 is a perspective view of a bottle carrier
showing my new design.

Fig. 2 is an end elevation of the bottle carrier.

Fig. 3 is a side elevation of the bottle carrier.

Fig. 4 is a plan view of the bottle carrier.

I claim:

The ornamental design for a bottle carrier, as
shown.

GRANT M. ACTON.
